UNITED STATES PATENT OFFICE.

FELICE CORTI, OF MILAN, ITALY.

CARBURETOR.

Application filed July 8, 1918. Serial No. 243,955.

To all whom it may concern:

Be it known that FELICE CORTI, of Milan, Italy, has invented certain new and useful Improvements in Carburetors, of which the 5 following is a specification.

This invention relates to a carburetor for internal combustion engines of the type in which the air and fuel supplies are simultaneously regulated so as to maintain a constant-mixture-ratio.

It has previously been proposed in carburetors of the type referred to, to regulate the air inlet by means of two cylinders simultaneously rotating in opposite directions 15 in the vicinity of the spray nozzle, the air passage areas depending on the shape of cavities formed in the said cylinders.

It is also known to use a carburetor in which the spray nozzle consists of two 20 tubes, viz., one stationary and the other rotatable, capable of revolving one on the other in such a way that by the effect of the rotation, the spray holes are in partially or in fully opened or closed positions.

25 The invention also consists in the improved carburetor as hereinafter more particularly referred to.

The carburetor forming the object of the invention shown diagrammatically in the 30 annexed drawing, in which:

Figure 1 is a sectional elevation of the carburetor;

Figure 2 is a side view of the same, showing the air conduit partially in section.

35 Figures 3 and 4 are horizontal sections through Figure 1 showing two different positions both of the cylinders regulating the air inlet and of the rotating tube of the spray nozzle.

40 Figure 5 shows the spraying nozzle in larger scale partly in elevation and partly in section.

Figure 6 is a plan view of same.

Figure 7 is a detail of the spraying nozzle.

45 The working principle of the improved carburetor will be understood by reference to Figure 1. The benzine from a constant level chamber flows through a duct —5— in bottom into the spray nozzle, which is of

50 special design and consists of two parts —11— and —14— arranged one inside the other in such a way that part —14— can be revolved upon part —11—. The spray nozzle is shown in detail in Figures 5 and 6, 55 from which it may be seen that it is built up of two tubes —11— —14— arranged one

inside the other and closed by spherical, upper surfaces —12— —15—. The inner tube —11— is stationary and the outer tube can revolve on the inner one. The two tubes 60 are held together by a spring —16— bearing against flanged projections —18— formed at the bottom of the outer tube —14—, and against similar projections —17—, formed on the inner tube. The said flanged projections are so designed as to permit of the two tubes being readily fitted into one another. Two longitudinal slots formed in the outer tube permit of the inner tube being slid into it, said slots being sufficiently wide to permit angular movements on the tube —11—. 65

The ends of spring —16— are respectively fixed to one of the projections —17— and —18—.

The fixed inner tube and the revolving 70 outer one are provided with one or two spray holes —13— —16—, through which the benzine flows under the action of the engine suction; the two holes being arranged at a certain distance from the center line of the 75 nozzle. It will be readily understood that when the outer tube —14— is caused to turn on the inner tube —11—, the holes in the one tube may accurately register with those of the other tube, or the holes may be partially or entirely closed. In the former case the benzine outlet area has its maximum 80 value, from which it can be gradually reduced to zero.

The air outlet takes place through lateral 90 apertures —37— in body —1—; the air and benzine mixture is formed in the chamber —2—, in the vicinity of the spraying nozzle; and it is thence carried to the motor inlet by a pipe. The air passage round the end of the nozzle is adjusted by two cylinders 95 —7— —8—, which turn in opposite directions to one another on their parallel spindles —7'— —8'—. According as the two cylinders revolve in one direction or in the other they afford a gradually increasing or decreasing area for the air passage. Thus in the cylinder position represented in Figures 1 and 3 the annular air passage —36— is almost entirely closed; and in that represented in Figure 4 (in which the cylinders have turned through 180° with respect to Figure 3) the annular air passage —36— is of maximum diameter for the maximum amount of air. This is obtained by forming on each cylinder 100 the cavities —9— —10— of a conoid form. It will thus be seen that by rotating the two 105

cylinders the air passage round the upper end of the nozzle can be increased or decreased at will. The cylinder spindles —7—8— are supported in the walls by the 5 body —1—.

The gears regulating the air inlet and those regulating the benzine inlet are operated simultaneously in such a way that, when the air passage area is increased, the 10 benzine passage area is also increased though in a different proportion, and the ratio of air to benzine is maintained constant.

The above mentioned simultaneous control of the two gears is obtained in the following 15 manner: The cylinders —7—8— are provided with two grooves —21— in which a thin, flexible wire rope —19— is wound (Fig. 2), the rope end being connected to a rod —22— sliding in tube —23— and duly 20 actioned by the conductor from outside.

Cylinders —7—8— are further provided with toothed wheels —25—26— meshing with one another.

When a pull is exerted on rope —19— 25 cylinder —8— is rotated and cylinder —7— is driven by the latter through the gears —26—25—.

A suitable spiral spring 10 tends to bring the cylinders back into closing position. 30 This spring 10 is arranged in a box with one end secured to the box and the other end 27 secured to the cylinder spindle 8'.

In order that at the same time the outer 35 tube of the nozzle may be rotated about its own axis, thus simultaneously regulating the benzine inlet, a disc or cam —29— rotating along with cylinder —7— is provided.

The inner surface of the disc —30— is 40 bevelled, and a connecting link —31— bears with one end —33— against this surface, the link being connected to the lug —32— projecting from outer nozzle tube —14—. Said link crosses the body —1— without touching the cylinders —7—8— or the nozzle.

45 When the air passage, through the de-

scribed rotation of cylinders —7—8— is varied the cam —29— either pushes or releases the rod —31—, thereby rotating tube —14— and adjusting the air passage through holes —13—16—.

The spring —16— acts as a return spring. The outer tube —14— being thus rotated on the inner tube —11—, a gradual opening or closure of the nozzle or nozzles will be obtained. The contact between the rod end 55 —33— and the bevelled surface —30— of the disc —29— is ensured by spring —16—.

The object is thus obtained of accurately proportioning the amount of benzine to the amount of air at all speeds of the engine, 60 appreciable economy being thus realized.

Having now particularly described and ascertained the nature of my said invention and in what manner the same is to be performed, I declare that what I claim is:— 65

In a carburetor, in combination, a casing, a spring governed and manually operable variable air control, a spraying nozzle associated with said air control and composed of tubular sections one of which is rotatable 70 with respect to the other, a lug projecting from the rotatable section, a rod link slidably mounted in the casing and having its medial portion connected with said lug, a beveled disk associated with the air control 75 and operable therewith and acting against the end of the rod link so as to regulate the operation of the rotatable tubular section of the spraying nozzle consistent with the operation of the variable air control, and a return spring associated with the other end of the rod link.

In testimony whereof I affixed my signature, in presence of two witnesses.

FELICE CORTI.
